[57] CLAIM

The ornamental design for a belt-supported canister holster, as shown and described.

DESCRIPTION

FIG. 1 is a front perspective view of a belt-supported canister holster showing my new design;

FIG. 2 is a top plan view thereof;

FIG. 3 is a bottom plan view thereof;

FIG. 4 is a rear elevation view thereof;

FIG. 5 is a left side elevation view thereof, the right side elevation view being a mirror image thereof;

FIG. 6 is a front elevation view thereof;

FIG. 7 is a sectional view taken along line 7—7 of FIG. 2;

FIG. 8 is a sectional view taken along line 8—8 of FIG. 2;

FIG. 9 is a front perspective view of a second embodiment of the belt-supported canister holder shown in FIG. 1;

FIG. 10 is a top plan view thereof;

FIG. 11 is a bottom plan view thereof;

FIG. 12 is a rear elevation view thereof;

FIG. 13 is a left side elevation view thereof, the right side elevation view being a mirror image thereof;

FIG. 14 is a front elevation view thereof;

FIG. 15 is a sectional view taken along line 15—15 of FIG. 10; and,

FIG. 16 is a sectional view taken along line 16—16 of FIG. 10.

The broken lines representing a belt are shown for illustrative purposes only.
